UNITED STATES PATENT OFFICE.

R. Z. EMMERT, OF BANNISTER, MICHIGAN.

PUMP.

1,280,001.

Specification of Letters Patent. Patented Sept. 24, 1918.

Application filed January 7, 1916. Serial No. 70,848.

To all whom it may concern:

Be it known that I, R. Z. EMMERT, a citizen of the United States, residing at Bannister, in the county of Gratiot and State of Michigan, have invented certain new and useful Improvements in Pumps, of which the following is a specification.

My present invention has relation to the class of pumps, and the main object thereof resides in the provision of an improved pump that includes novel means whereby the flow of fluid may be selectively directed through the spout thereof, or through the conduits for conveying the fluid to a point or points remote therefrom, without necessitating the stopping of the pump or in fact, reducing the velocity of flow to any extent.

A further object of my invention is to provide a device of the character in question that is extremely simple in construction, strong and durable, and highly practical both from the standpoint of the manufacturer and the standpoint of the user; and which, it is believed may be manufactured at a minimum cost.

Various other objects and advantages will become apparent during the continuance of the following description.

These and other objects which will become apparent are accomplished by such means as are shown in their preferred form in the accompanying drawings, described in the following specification and then more specifically pointed out in the appended claims.

In the drawings wherein like characters designate like parts throughout the several views:

Figure 1 is a vertical sectional view of my improved pump showing the same as in its preferred embodiment,

Fig. 2 is a fragmentary view of the pump showing in detail the valve for controlling the flow of fluid to the spout or faucet there- of, and

Fig. 3 is a horizontal sectional view taken on line 3-3 of Fig. 1.

In reducing my invention to practice, I provide a pair of cylinder sections 10 and 11, respectively, whose adjacent ends are removably attached to a connecting sleeve 12, in a manner whereby they are held in axial alignment with each other. The lower section 11 has connection with a pipe 13, which

is to extend into a well or other source of fluid supply, through the medium of a cap 14, while the upper cylinder 10 detachably carries a head 15, as at 16 that in turn carries an insert or inner cylinder 17, as clearly shown in Fig. 1. The insert 17 forms practically the entire upper piston cylinder of the device, although in a sense, it may be termed means for guiding a head, such as will be presently described. The piston head 15 which is carried by the upper cylinder 10 is provided with a central opening 18 for receiving the piston rod of the pump, such as will be presently described.

A valve 19 is positioned within the lower cylinder 11, so as to normally close the upper end of the pipe 13, and is provided with a depending weight 20 whereby it may be more readily seated in the proper position. The valve 19 is also provided with a detachable bail 21 so that it may be easily removed from the cylinders when occasion so requires. Furthermore, the tapering body of the valve also permits the proper centering thereof by the weight 20.

The piston rod 22 is arranged to extend through the opening 18 of the head 15 into the insert 17 and the lower cylinder 11. The piston head 23 is carried at the lower end of the rod, so as to operate in the cylinder 11 and is provided with openings 24 which are normally closed by a flap valve 25. This piston head is also provided with a plurality of packing rings 26 which fit snugly against the inner wall of the respective cylinder and form a comparatively water tight connection therewith. A second piston 27 is mounted on the rod 22 as at 28, so as to operate within the insert 17, and is provided with packing rings 29 for engagement with the walls of the insert. Consequently it will be seen that during the upward movement of the piston rod, a suction will be created in the lower cylinder 11 such as will cause the unseating of the valve 19 and the drawing of fluid through the pipe 13 into the lower cylinder. However, when the rod starts its downward stroke the valve 19 will be immediately seated on the upper end of the pipe 13, while the fluid in the lower cylinder 11 will be forced upwardly through the openings 24 of the piston 23, by reason of the unseating of the flap-valve 25, and enter the space between the pistons.

From this space the fluid will be dispensed in a manner that will be hereinafter set forth.

The connecting sleeve 12 is provided with 5 a second and preferably smaller sleeve 30 which has communication therewith through the medium of a way 31. A cylinder 32 is mounted in the upper end of the sleeve 30, as shown in Fig. 1, while any number of conduits or other conducting members 33 may 10 be directly or indirectly connected with the lower end of the sleeve. At its upper end, the cylinder 32 is connected with a member 34, which in turn supports the cylinder head 15 35 which carries the outlet spout 36. To allow communication between the cylinder 32 and the cylinder head 35, the member 34 is provided with a through opening such as indicated by the numeral 37. The member 34 20 supports a bracket 38 having arms 39 through which extends the piston rod 22. The bracket 38 also supports a handle 40, as at 41 whereby the piston rod may be actuated in the usual manner.

25 Valves 42 and 43, respectively, are employed for the purpose of closing the end of the conduit 33 and the opening 37 of the member 34, so as to provide for selectively dispensing the fluid from the pipe either to 30 the conduit 33 or to the spout 36. The valves 42 and 43 are carried upon a rod 44 that extends through the cylinder 32 in such a manner that when the lower valve 42 is in a closed position, the upper valve 43 will permit the fluid to flow from the cylinder 32 to 35 the head 35 through the opening 37 and hence to the spout or faucet 36. The upper end of the rod 44 is passed through an opening 45 in the head 35, the stuffing boxes 46 40 forming a comparatively tight connection therewith, however, the upper end of this rod may be screw-threaded as at 47 for engagement with a member 48 that is carried by the cylinder head 35 intermediate the 45 ends of the openings 45, so that the rod 44 may be adjusted so as to manipulate the valves 42 and 43. The rod 32 may be also provided with an operating wheel 49 whereby movement thereof will be greatly facilitated.

50 In the operation of my improved pump, it will be seen that the fluid will be forced from the pump cylinders through the way 31 to the sleeve 30. Consequently when the parts 55 are in the position shown in Fig. 1 this fluid will pass upwardly through the cylinder 32 and hence to the spout or faucet 36 by way of the opening 37 and the cylinder head 35. On the other hand, by properly adjusting 60 the rod 44, the valve 43 may be moved into a closed position, while the valve 42 may be opened to permit the fluid to flow directly into the conduit 33.

65 From the foregoing it will be recognized that I have provided means for adequately

controlling the flow of fluid from the pump structure, so as to direct the same either through the usual outlet spout of the pump or through the conduit for conveying the same to a point remote from the pump.

70 From the foregoing it is believed that the advantages and main features of my invention will be readily understood and therefore further detailed description is deemed unnecessary.

75 In reducing my invention to practice, I find that that form referred to herein as the most practical and preferred embodiment is the most efficient; but realizing that certain conditions will necessarily vary in concurrence with the adoption of my device, I desire to emphasize the fact that various minor changes in the details of construction and in the arrangement and combination of parts may be resorted to when required without departing from the spirit and scope or sacrificing any of the advantages of my invention as defined in the appended claims.

80 Having thus fully described my invention what I claim as new and desire to secure by Letters Patent is:

85 1. In a pump, the combination with a piston-rod, a piston carried by the piston-rod, a valve, adjusting means for said valve, a lever for reciprocating said piston-rod, and a hollow device having an inlet opening and an outlet opening, and being co-operative with 90 said piston for receiving and discharging fluid; of an integral body secured on the top of said hollow device and formed with a valve seat and with a guide for said piston-rod and with a support upon which said lever is fulcrumed, said valve seat being co-operative with said valve for controlling the flow of fluid through said hollow device.

95 2. In a pump, the combination of a pump cylinder, a piston therein, a piston-rod, a discharging cylinder connected with the pump, a bracket at the upper end of the discharge cylinder and forming a guide for the piston rod, a lever mounted on the bracket and connected with the piston rod, a valve for controlling the flow through the discharging cylinder, an outlet head for the discharging cylinder mounted on the said 100 bracket, and valve adjusting means carried by the said outlet head.

105 3. In a device of the character described, a pair of pump cylinders, a sleeve connecting said cylinders at their adjacent ends to retain the same in substantial alinement, a pipe having connection with one of said pump cylinders, a valve to normally seat upon the upper end of said pipe, a head adjustably carried by the other of said cylinders, an insert carried by said head to be positioned in one of said cylinders, said head provided with a through opening, pistons mounted to operate in one of said pump cylinders and said 110 insert, common means to connect and operate

- said piston heads, a second sleeve associated with said first-mentioned sleeve, said sleeves provided with a way communicating there-between, a conduit fixed at one end to said 5 second-mentioned sleeve, another cylinder having one end adjustably connected with said second-mentioned sleeve, a member adjustably mounted at the other end of said last-mentioned cylinder, a bracket on said 10 member to support said piston operating means, a head carried on said member, said member provided with a through opening to establish communication between said last-mentioned head and said second-mentioned 15 cylinder, an outlet spout carried by said last-mentioned head, and a valve to control the flow of fluid from said pump cylinders to said conduit and said outlet spout, as and for the purpose specified.
- 20 4. The combination with a source of fluid supply, of a sleeve provided with an opening to receive the fluid, a conduit connected with one end of said sleeve, a cylinder connected with the other end of said sleeve, a member 25 extending transversely of the upper end of said cylinder, said member provided with a through opening, a head mounted on said member, an outlet spout carried by said head, a rod mounted to extend longitudinally of
- 35 said cylinder and said sleeve, valves mounted on said rod to selectively close the end of said conduit and the opening through said member, and means to actuate said rod to move said valve, as and for the purpose specified.
5. The combination with a source of fluid supply, of a sleeve having an opening to receive the fluid, a conduit connected at one end to said sleeve, a cylinder having one end connected with said sleeve, a member mounted transversely of the upper end of said cylinder, said member provided with a through opening, a cylinder head carried on said member, an outlet spout connected with said cylinder head, a rod journaled through the upper end of said head to extend longitudinally of said cylinder and said sleeve, valves mounted on said rod in a manner to close said conduit and open said member opening conversely, and means to actuate said rod so as to move said valves, as and for the purpose specified.

In testimony whereof I affix my signature in presence of two witnesses.

R. Z. EMMERT.
